EQUIPMENT FOR AUTOMATICALLY CONTROLLING SINGLE PHASE MOTORS

Leon Heidmann, Paris, France, assignor to Forges et Ateliers de Constructions Electriques de Jeumont, Paris, France, a corporation of France

Application February 17, 1953, Serial No. 337,395

Claims priority, application France
February 29, 1952

9 Claims. (Cl. 318—390)

1 The present invention relates to equipment for controlling single phase motors by means of a plurality of individual contactors of the electromagnetic or electropneumatic type. The equipment in accordance with the invention is useful particularly, but not exclusively, for controlling single phase traction motors by means of starting contactors connected with the tappings of a regulating transformer.

The problem involved in such a control system is to close first a predetermined group of contactors connected with certain taps of the transformer, for example with three or four taps, for the purpose of establishing a first step in the starting sequence, then to open the first contactor of this group and replace it by a new contactor connected with another tap of the transformer, and so on.

One of the objects of the invention is to provide simple equipment for effecting these operations with maximum guarantee of proper control by means of a master controller which permits a completely automatic, or partially automatic, start subordinated to a single acceleration relay.

Another object of the invention is to prevent the simultaneous closing of contactors, which would result in short circuits or overloads.

According to the present invention, equipment for controlling single phase motors by means of a master controller and acceleration relay and individual starting contactors connected with the respective taps of a regulating transformer is characterized by the fact that the operating coil for each individual contactor is connected in turn with three energizing wires, the first being a starting wire which energizes the coil by means of auxiliary contacts which assure the proper order of closing of the contactors, the second being a holding wire which energizes the same operating coil by means of auxiliary holding contacts and the third being a wire for opening the contactors, this opening wire being connected with the coil through auxiliary transfer contacts and being also connected with the contacts of the acceleration relay in such a way as to ground the opening wire when the acceleration relay contacts are closed and thereby open the starting contactors.

The nature and objects of the invention will more fully appear from the following description and claims in conjunction with the accompanying drawings which show a circuit diagram of equipment embodying the invention.

In the drawing there is shown, by way of ex-

ample, an embodiment of the invention having twelve individual starting contactors and a master controller with four operating positions. The individual contactors 1 to 12 are connected to the respective taps of a regulating transformer T_r and to four bus bars m , n , o and p . The contactors are connected to the bus bars in predetermined sequence. For example, as shown in the drawings, contactors 1, 5 and 9 are connected to bus bar m , contactors 2, 6 and 10 are connected to bus bar n , contactors 3, 7 and 11 are connected to bus bar o and contactors 4, 8 and 12 are connected to bus bar p . The single phase motors M are connected to the bus bars through main line contactors L_1 and L_2 and three transition inductances X_1 , X_2 and X_3 .

An acceleration relay A has contacts d_1 and three operating coils a_1 , b_1 and c_1 . The coil c_1 is wound of heavy wire and is connected in series with the return line of the motors M being shunted by a resistance r , so that it is energized by a fraction of the motor current.

The master controller K is illustrated in the form of a multi-position rotary switch having an operating handle H and four operating positions or steps I to IV. The master controller is connected with a suitable source of electrical current Q , to supply current to the various control circuits that will now be described.

In all of the operating steps I to IV, the master controller K supplies current to an operating wire f_0 to which an arming coil b_1 of the acceleration relay A and a starting wire mn are connected in series. A holding wire mt and an opening wire ov are connected directly to the operating wire f_0 and a voltage is hence applied to them in all of the operating steps I to IV. The wire f_0 also supplies current to the coils BL_1 and BL_2 of the line contactors L_1 and L_2 .

The line contactors L_1 and L_2 have auxiliary contacts t_1 and t_2 which are closed when L_1 and L_2 are open and are connected in the circuit of the starting wire mn , the two auxiliary contacts t_1 and t_2 being arranged in parallel with one another. The operating coils BL_1 and BL_2 of the line contactors L_1 and L_2 are connected in parallel with one another and are connected to the operating wire f_0 by two parallel wires ma and je . In the wire ma , there is a normally open auxiliary l_1 carried by one of the line contactors L_1 or L_2 . In the wire je , there is a normally closed auxiliary contact l_2 carried by one of the line contactors L_1 or L_2 and a normally open auxiliary contact l_3 carried by the individual contactor 1, the contacts t_2 and l_3 being con-

50 nected in series with the operating wire f_0 . In the wire ma , there is a normally open auxiliary l_4 carried by one of the line contactors L_1 or L_2 . In the wire je , there is a normally closed auxiliary contact l_5 carried by one of the line contactors L_1 or L_2 and a normally open auxiliary contact l_6 carried by the individual contactor 1, the contacts t_2 and l_6 being con-

nected in series. This arrangement assures that the line contactors L_1 and L_2 cannot close unless the contactor 1 is closed first. As soon as the two line contactors L_1 and L_2 are closed, the auxiliary contact 1_1 closes the upper holding wire mn while the contact 1_2 opens the lower closing wire re . This keeps the line contactors L_1 and L_2 closed after the opening of the contactor 1.

Each of the individual contactors 1 to 12—
which may be of the electromagnetic or electro-pneumatic type—has an operating coil designated, respectively, B_1 to B_{12} and auxiliary or interlocking contacts which belong to six series. The interlocking contacts of the series 1a to 12a are normally closed and are connected in series with one another in the starting wire mn . The interlocking contacts of the series 1b to 12b are normally open and are connected in branch lines leading from the starting wire mn to the operating coils B_2 to B_{12} of the individual contactors 2 to 12. It will be seen that branch lines leading to the operating coils B_2 , B_3 and B_4 are connected with the starting wire mn between the master controller K and the first of the normally closed auxiliary contacts 1_1 to 1_{12} . The branch line leading to operating coil B_5 is connected to the starting wire mn between contacts $1a$ and $2a$, the operating coil B_6 is connected to the starting wire mn between contacts $2a$ and $3a$, etc. It will be further noted that normally open auxiliary contact $1b$ is in the branch line leading to operating coil B_2 , auxiliary contact $2b$ is in the branch line leading to operating coil B_3 , etc. In designating the operating coils and the auxiliary contacts, the numeral indicates in each instance the individual contactor 1 to 12 to which the operating coils and auxiliary contacts belong. The operating coil B_1 is connected to the starting wire mn at a point beyond all of the series-connected normally closed auxiliary contacts 1a to 12a and in series with the normally closed contacts 1_1 and 1_2 of the line contactors L_1 and L_2 .

The arrangement described above assures the proper sequence of operation of the individual contactors 1 to 12. The operating coil B_1 of the contactor 1 cannot be energized by the starting wire mn unless all of the contacts of the first series 1a to 12a are closed, which means unless all of the contactors 1 to 12 are open. Moreover, the auxiliary contacts 1_1 and 1_2 of the line contactors L_1 and L_2 must be closed, which means that these line contactors are open. Operating coil B_2 of the contactor 2 can be energized to close the contactor only after auxiliary contact $1B$ has been closed by the closing of contactor 1. In like manner, each succeeding contactor can be closed only after the preceding contactor has been closed. Hence, proper starting conditions and proper sequence of operation of the contactors are assured.

The third and fourth series of auxiliary contacts provided on the contactors 1 to 12 are designated, respectively, $2c$ to $11c$ and $1d$ to $11d$. The auxiliary contacts $2c$ to $11c$ are normally closed and are connected in series, respectively, with the normally open auxiliary contacts $1b$ to $10b$ in the branch lines leading from the starting wire mn to the operating coils B_2 to B_{11} . The auxiliary contacts $1d$ to $11d$ are normally open and are in branch lines leading from the holding wire mt to the operating coils B_1 to B_{11} . The auxiliary contacts $2c$ to $11c$ and $1d$ to $11d$ provide for holding the contactors 1 to 11 closed and may hence be designated as holding contacts. As described above, current for initially energizing

the operating coils B_1 to B_{12} of the individual contactors 1 to 12 is supplied by the starting wire mn . This current also flows through the arming coil b_1 of the acceleration relay A which is thereby energized to close this relay. However, this initial energization is soon interrupted and replaced by the holding energization provided by current supplied from the holding wire mt through the holding contacts $1d$ to $11d$ and the corresponding auxiliary contacts of the series e and f described below. So that the transition from starting to holding is effected without interruption of current in the coils B_1 to B_{12} , an overlap is provided in the operation of the series c and series d contacts, so that the series d contacts close before corresponding c series contacts open.

The ninth and sixth series of auxiliary contacts with which the individual contactors 1 to 12 are provided are transfer contacts and are designated as series e and series f, respectively. Auxiliary contacts $4f$ to $11f$ are connected in series with the holding contacts $1d$ to $8d$, respectively, in the branch lines connecting the operating coils B_1 to B_8 with the holding wire mt and are normally closed. Auxiliary contacts $4e$ to $11e$ are normally open and are in branch lines connecting operating coils B_1 to B_8 with the opening wire ov , the auxiliary contacts $4e$ to $11e$ being also connected in series with the holding contacts $1d$ to $8d$. It will be noted that auxiliary contacts $4e$ and $4f$ of individual contactor 4 are connected in circuit with the operating coil B_1 of contactor 1, auxiliary contacts $5e$ and $5f$ of contactor 5 are connected in the circuit of the operating coil B_2 of contactor 2, etc. The auxiliary contacts of series e and f transfer the control of the operating coils from the holding wire mt to the opening wire ov . Thus, for example, when contactor 4 is open and contactor 1 is closed, the operating coil B_1 of contactor 1 is energized by current supplied from the holding wire mt through contacts $4f$ and $1d$. If contactor 4 is now closed, auxiliary contact $4f$ will be opened while auxiliary contact $4e$ will be closed, so that the operating coil B_1 is now connected through contacts $1d$ and $4e$ with the opening wire ov . By being transferred from connections with the holding wire mt to connections with the opening wire ov , the operating coils of the contactors are put under the control of the acceleration relay A, as will be explained below. An overlap is provided in the operation of the series e and series f auxiliary contacts, so that series e contacts will be closed before series f contacts are opened, to avoid interruption in the current supplied to the operating coils of the contactors.

In addition to the connections described above, there are three control wires f_1 , f_2 and f_3 leading from the master controller K. The first control wire f_1 is connected through the holding contact $1d$ with the operating coil B_1 of the contactor 1. The second control wire f_2 is connected in similar manner to the operating coil B_4 and the third control wire f_3 is connected to the operating coil B_7 . In its first step of operation I, the master controller K supplies current to all of the control wires f_1 , f_2 and f_3 . In the second step II of the master controller, the control wire f_1 is de-energized. In the third step III, the control wire f_2 is de-energized and in the fourth step IV, the control wire f_3 is de-energized. The function and purpose of the control wires f_1 , f_2 and f_3 will be described more fully below.

With the circuits shown and described, the in-

dividual contactors 1 to 12 are closed and opened in such a way that in each step of the operation, with the exception of the first, a group of four contactors are closed, the remaining contactors being open. As additional contactors are successively closed in sequence, a corresponding number of previously closed contactors are opened, so that the number of contactors closed at any one time is four.

Starting with the line contactors L1 and L2 and all of the individual contactors 1 to 12 open, and with the acceleration relay A de-energized, movement of the main controller K to any of the four positions I to IV applies voltage to the operating wire fo and, through it, to the coil b1 of the acceleration relay A and to the starting wire mn. As the auxiliary contacts ta to t2 and the auxiliary contacts t1 and t2 are all closed, the operating coil B1 of the contactor 1 is energized to close this contactor. This results in closing the holding contact 1d, so that the contactor 1 is kept closed, and also closing the auxiliary contacts 1g in the line fe, so as to energize the operating coils BL1 and BL2 to close line contactors L1 and L2. The line contactors L1 and L2 are then held closed by current supplied through the holding contact 1d in line ma. The closing of contactor 1 also closes auxiliary contact 1b in the branch line leading from the starting wire mn to the operating coil B2 of the contactor 2, so that the latter contactor is closed and is held closed by the holding contact 2d. In like manner, contactors 3 and 4 are successively closed.

The closing of the contactor 4 closes the auxiliary contacts 4e and opens contacts 4f, so that the holding circuit of the operating coil B1 of the first contactor 1 is transferred from the holding wire mt to the opening wire ov. During this operation, the currents in the wires ov and mt are limited and balanced by means of control resistances r1, r2 and r3. The acceleration relay A, which was initially opened by current flowing through the operating wire fo, the coil b1 and starting wire mn, is kept open by a fraction of the motor current flowing through the coil c1 which, as described above, is in the return line from the motors and is shunted by a resistance r. As the motors accelerate, the starting current is progressively reduced. When a predetermined reduction in the motor-starting current has occurred, the acceleration relay A drops and, by its contacts d1, grounds the opening wire ov. Consequently, the operating coil B1, which was energized by the opening wire ov, is de-energized, so that the contactor 1 opens and its auxiliary contact 1a closes. As auxiliary contacts 4b are already closed, current is now supplied through the wire fo, coil b1, starting wire mn and contacts 1a, 4b and 5c to the operating coil B5, to close contactor 5. This contactor is then held closed by its holding contact 5d. The closing of contactor 5 closes contacts 5e and opens contacts 5f, so that the control of operating coil B2 is transferred from the holding wire mt to the opening wire ov. Hence, the next time the acceleration relay drops—upon predetermined decrease of the motor-starting current—contactor 2 will be de-energized and contactor 6 will be energized. The successive operation of the other contactors occurs in like manner. Thus, contactor 3 opens when contactor 7 closes, contactor 4 opens when contactor 8 closes, etc. Thus, at any one time, there is a group of four contactors closed.

During the closing of each contactor, a short

current impulse passes through the wire mn and the coil b1 of the acceleration relay A and lifts the armature of the relay to open the contacts d1. Thereafter, the relay is held by the starting current which flows through the lower coil c1 until—due to acceleration of the motors—the starting current decreases to a predetermined point, whereupon the acceleration relay A drops and initiates a new step of the starting operation, as described above.

It will be seen that the starting of the motors M proceeds automatically, being controlled by the acceleration relay A. However, the point to which the starting operation proceeds depends on the position of the master controller K. With the master controller at step I, current supplied through the wire f1 keeps the contactor 1 from dropping by continuing to energize the operating coil B1, even though the supply of current from the opening wire ov is interrupted by the dropping of the acceleration relay and the resulting grounding of the wire ov. Since contactor 1 is kept closed, the auxiliary contacts 1a remain open and hence current cannot be supplied from the starting wire mn to the next contactor 5. Thus, with the master controller set at step I, the starting operation cannot proceed beyond the closing of the first group of contactors 1 to 4. With the master controller K set at step II, the control wire f2 supplies current to the operating coil B4 to keep the contactor 4 from opening. The progress of the starting operation is thereby halted at a stage in which contactors 4, 5, 6 and 7 are closed. In like manner, with the master controller K set at step III, the control wire f3 keeps the contactor 7 from opening, so that the progress of the starting operation is halted at a stage in which contactors 7, 8, 9 and 10 are closed. This has the result that, in the starting operation, the equipment does not go beyond the steps corresponding to the positions of the handle on the master controller. If the handle is set for the last step, the starting operation will proceed uninterrupted.

The coil a1 of the acceleration relay A is connected by a wire s to the contact f1 through which current is supplied from the operating wire fo. This contact is operated manually, for example by downward movement on the pivoted handle H of the master controller K. If, during the progress of the automatic start, the handle H is pressed downwardly to close the contact f1, the upper coil a1 of the acceleration relay is energized, so that the armature of the relay is held up and the progress of the starting operation is interrupted.

It will be understood that the system shown and described represents only one example of embodiment of the invention and that many modifications can be made within the scope of the present invention as defined by the appended claims.

What I claim and desire to secure by Letters Patent is:

1. In equipment for automatically controlling single phase motors, a regulating transformer with a plurality of taps, a plurality of individual contactors each having an operating coil, main contacts and auxiliary contacts comprising interlocking contacts, holding contacts and transfer contacts, connections between the main contacts of the contactors and said taps respectively and connections between the main contacts of the contactors and said motors so that the closing of said main contacts connects said

7

motors with the respective taps of said transformer, an acceleration relay having cooperating contacts, a master controller, and connections between the aforesaid elements comprising three wires connected with and excited by the master controller in all positions of said controller, the first of said wires being a starting wire which is connected with the operating coils of said contactors through said interlocking contacts which are connected in series to assure a predetermined order of closing of said contactors, the second of said wires being a holding wire which is connected to the operating coil of each contactor through the holding contacts of the respective contactor so as to hold the contactor closed after it has been closed by the starting wire, and the third of said wires being an opening wire which is connected on one hand with the operating coils through the respective transfer contacts and on the other hand with one of said contacts of the acceleration relay, the other of said cooperating contacts being connected with ground to ground said opening wire when the cooperating contacts of the acceleration relay are closed.

2. In equipment for automatically controlling single phase motors, a regulating transformer having a plurality of taps, a plurality of contactors each having an operating coil, main contacts and auxiliary contacts comprising interlocking contacts, holding contacts and transfer contacts, an acceleration relay having cooperating contacts, a master controller, and connections between the aforesaid elements comprising connections between the main contacts of the contactors and said taps respectively and connections between the main contacts and said motors so that the closing of said main contacts connects the motor with the respective taps of the transformer, and three wires connected with and excited by the master controller in all positions of said controller, the first of said wires being a starting wire which is connected with the operating coils of the contactors through said interlocking contacts which assure the closing of the contactors in predetermined order, said interlocking contacts comprising normally closed contacts connected in series with one another and normally open contacts connected in parallel with one another and interposed between the starting wire and the operating coils of the respective contactors, the second of said wires being a holding wire which is connected to the operating coil of each contactor through the holding contacts of the respective contactor so as to hold the contactor closed after it has been closed by the starting wire, and the third of said wires being an opening wire which is connected on one hand with the operating coils through the respective transfer contacts and on the other hand with one of said contacts of the acceleration relay, the other of said cooperating contacts being connected with ground to ground said opening wire when the cooperating contacts of the acceleration relay are closed.

3. Equipment according to claim 1, in which said holding contacts comprise normally closed contacts interposed between the starting wire and the operating coils of the individual contactors and normally open contacts interposed between said coils and the holding wire, said contacts being spaced to provide an overlap between the opening of the normally closed con-

8

tacts and the closing of the normally open contacts.

4. Equipment according to claim 1, in which said transfer contacts comprise normally open contacts interposed between said operating coils of the individual contactors and said opening wire and normally closed contacts interposed between said coils and said holding wire, said contacts being spaced to provide an overlap between the opening of said normally closed contacts and the closing of said normally open contacts.

5. In equipment for automatically controlling single phase motors, a regulating transformer having a plurality of taps, a plurality of individual contactors each having an operating coil, main contacts and auxiliary contacts comprising interlocking contacts, holding contacts and transfer contacts, an acceleration relay having cooperating contacts, a master controller having a handle and a contact operable by said handle, and connections between the aforesaid elements comprising connections between the main contacts of said contactors and said taps respectively and connections between said main contacts and said motors so that the closing of said main contacts connects the motors with the respective taps of the transformer, and three wires connected with and excited by the master controller in all positions of said controller, the first of said wires being a starting wire which is connected to the operating coils of said contactors through said interlocking contacts which are connected in series with one another to assure a predetermined order of closing of said contactors, the second of said wires being a holding wire which is connected to the operating coils of said contactors through the holding contacts of the respective contactors so as to hold the contactor closed after it has been closed by the starting wire, and the third of said wires being an opening wire which is connected on one hand with the operating coils of the respective contactors through said transfer contacts and on the other hand with one of the contacts of said acceleration relay, the other of said contacts of the acceleration relay being connected to ground to ground said opening wire when the acceleration relay is closed, said acceleration relay having an operating coil connected in series with the motors and shunted by a resistance, an armature coil connected with said starting wire and a coil for interrupting the starting sequence, said interrupting coil being connected with said contact operable by the master controller handle.

6. In equipment for automatically controlling single phase motors, a regulating transformer having a plurality of taps, a series of contactors each having an operating coil, main contacts and auxiliary contacts comprising interlocking contacts, holding contacts and transfer contacts, an acceleration relay having cooperating contacts, a master controller, and connections between the aforesaid elements comprising connections between the main contacts of the contactors and said taps respectively and connections between said main contacts and said motors so that closing of said main contacts connects the motors with the respective taps of the transformer, three wires connected with and excited by the master controller in all of its operative positions, the first of said wires being a starting wire which is connected with the operating coil of each contact, except the first, through interlocking contacts of the preceding contactor of said series to assure

a predetermined order of closing of said contactors, the second of said wires being a holding wire which is connected to the operating coils of said contactors through said holding contacts of the respective contactors to hold said contactors closed when they have been closed by said starting wire, and the third of said wires being an opening wire which is connected with operating coils of said contactors through transfer contacts of contactors which form a selected group depending upon the position of the master controller, said opening wire being connected to the contacts of said acceleration relay so as to be temporarily de-energized upon operation of said relay whereby a contactor earlier in said group is opened and a contactor later in the series is closed.

7. Equipment according to claim 6, in which control wires are connected to the operating coils of selected contactors and to said master controller, said control wires being selectively energized by the master controller in the respective operating positions of said controller to keep energized the coils of contactors to which energized control wires are connected and thereby interrupt the progress of a motor-starting operation by overriding the action of said opening wire and keeping said contactors from opening.

8. In equipment for automatically controlling single phase motors, a regulating transformer having a plurality of taps, a series of individual contactors each having an operating coil, main contacts and auxiliary contacts, line contactors having contacts and operating coils, an acceleration relay, a master controller, connections between the main contacts of said individual contactors and said taps respectively, and connections from the main contacts of said individual contactors to the contacts of said line contactors and from the contacts of said line contactors to the motors so that closing of the line contactors and of selected ones of said individual contactors connects the motors with the respective taps, connections from the master controller and the acceleration relay to the operating coils of said individual contactors to energize said contactor coils successively in predetermined sequence, and to de-energize successively coils of individual contactors earlier in the series so that a predetermined number of coils is energized at a time, connections from said master controller to the operating coil of said contactor through auxiliary contacts of the first individual contactor in said series to energize said last mentioned coil to close said line contactor only when said first individual con-

tactor is closed, and connections from said master controller to the operating coil of said line contactor through auxiliary contacts of said line contactor to maintain said line contactor closed after said first individual contactor has been opened.

9. In equipment for automatically controlling single phase motors, a regulating transformer having a plurality of taps, a series of contactors each having an operating coil, main contacts and auxiliary contacts, an acceleration relay having contacts, a master controller and connections between the aforesaid elements comprising connections between the main contacts of the contactors and the respective taps of the transformer and connections between said main contacts and said motors so that closing of selected ones of said individual contactors connects the motors with the respective taps of the transformer, three wires connected with and energized by said master controller, said wires being connected with the operating coils of said contactors through auxiliary contacts of said contactors and comprising a starting wire, a holding wire and an opening wire, said auxiliary contacts comprising interlocking contacts for connecting operating coils of said contactors with said starting wire to energize said coils, the operating coil of each contactor, other than the first, being connected with the starting wire through interlocking contacts of the next preceding contactor in the series to assure predetermined order of closing of the contactors, holding contacts for connecting said operating coils with the holding wire after the contactors have been closed and transfer contacts for transferring said operating coils from connection with the holding wire to connection with the opening wire, the operating coil of each contactor, other than a selected number of contactors at the end of the series, being connected with the transfer contacts of a contactor which is a selected number of positions later in said series, said opening wire being connected to the contacts of said acceleration relay so as to be temporarily de-energized upon operation of said relay to de-energize the operating coil of any contactor connected to said opening wire by said transfer contacts, so that as successive contactors are energized, a corresponding number of contactors earlier in the series are de-energized to maintain constant the number that are energized.
